UNITED STATES PATENT OFFICE

WILLIAM EDWARD HARRIS, OF NEW YORK, N. Y.

MANUFACTURE OF PAINT FROM METALLIC LEAD.

SPECIFICATION forming part of Letters Patent No. 327,678, dated October 6, 1885.

Application filed September 20, 1884. Serial No. 143,571. (No specimens.)

To all whom it may concern:

Be it known that I, WILLIAM E. HARRIS, of the city, county, and State of New York, have invented a new and Improved Process for 5 Making Metallic Paint from Lead, of which the following is a full, clear, and exact description.

The object of this invention is to facilitate the making of paint from metallic lead; and 10 the invention consists in the process of making paint from lead by burning the metallic lead in contact with coke, coal, or charcoal, and condensing the fumes, as will be herein-after fully described.

15 In carrying my invention into practical effect a furnace is heated to the temperature of about two thousand seven hundred degrees (2,700°) Fahrenheit with coke, coal, or charcoal. Lead is then mixed with coke, coal, or 20 charcoal in the proportions of about two tons of coke, coal, or charcoal to one ton of lead, and the mixture is placed in the furnace and burned. The lead will melt and run over, into, and through the coke, coal, or charcoal, and 25 that which runs through is placed upon the

top of the mixture as fast as it runs through until it, and all the lead that has lodged, has been vaporized. The fumes thus produced are conducted into and condensed in condensing-chambers, and will be found in a very finely- 30 divided condition, ready without grinding to be mixed with oil for paint.

The action is as follows: The lead as it melts and runs over the coke, coal, or charcoal becomes oxidized, forming oxide of lead, which, 35 coming in direct contact with the burning coke, coal, or charcoal, unites with its vapors, forming a fume that is condensed, and can be mixed with oil and used as a paint.

Having thus described my invention, what 40 I claim as new, and desire to secure by Letters Patent, is—

The process of making paint from metallic lead, and which consists in burning lead in contact with coke, coal, or charcoal, and condensing the fumes, substantially as described. 45

WILLIAM EDWARD HARRIS.
